UNITED STATES PATENT OFFICE.

LYNN P. McEACHRON, OF HOOSICK FALLS, NEW YORK.

TOOL-HOLDER.

1,221,556.

Specification of Letters Patent.

Patented Apr. 3, 1917.

Application filed November 24, 1916. Serial No. 133,234.

To all whom it may concern:

Be it known that I, LYNN P. McEACHRON, a citizen of the United States, residing at Hoosick Falls, in the county of Rensselaer and State of New York, have invented certain new and useful Improvements in Tool-Holders; and I do hereby declare the following to be a full, clear, and exact description of the invention, such as will enable others skilled in the art to which it appertains to make and use the same.

This invention relates to new and useful improvements in tool holders and the principal object of the invention is to provide a device for holding tools in proper position when the same are being sharpened.

Another object of the invention is to provide a device by which the tool may be accurately ground and held in proper position during the sharpening process.

A further object of the invention is to provide a device having suitable dials arranged thereon by means of which the user may readily determine the proper position in which the tool is to be held.

A still further object of the invention is to provide a novel form of clamp for holding the tool supporting head in various adjusted positions.

With these and other objects in view the invention consists in the novel combination and arrangement of parts which will be fully set forth in the following specification and accompanying drawings, in which:—

Figure 1 is an end view of a tool holder constructed in accordance with this invention.

Fig. 2 is a side view in elevation of Fig. 1.

Fig. 3 is a sectional view through the device.

Fig. 4 is a detail sectional view illustrating one of the clamps for holding the head against movement.

Fig. 5 is a detail fragmentary sectional view through the supporting bars for the head.

Fig. 6 is an enlarged detail sectional view through the head, and

Fig. 7 is a view similar to Fig. 6 taken at right angles thereto.

Referring to the drawings 1 designates one of the supporting legs of the device provided at its upper end with an enlargement 2 having an aperture 3 formed therein. The opposite supporting leg is designated by the numeral 4 and is provided near its

upper end with an enlargement 5 having an aperture 6 arranged therein. The lower ends of the legs are tapered as at 7 to form slides upon which the device is slideable. The apertures 3 and 6 are preferably circular to receive the trunnions of the rotatable shaft which will be more fully hereinafter described. Formed near the extreme upper end of each of the enlargements 2 and 5 are suitable rectangular apertures 8 for the reception of the ends of the connecting bar which will be more fully hereinafter described. Attached to the faces of the enlargements 2 and 4 are suitable blocks 9 provided with rectangular apertures which align with the apertures 8 and the connecting bar designated by the numeral 10 is provided with squared portions 11 at opposite ends which terminate in threaded portions 12 and project through the openings in the blocks 9 and the openings 8 as will be clearly seen upon reference to the drawings. Threaded on to the portions 12 of the bar are suitable nuts 13 by means of which the whole is held in assembled position.

The shaft for supporting the tool head consists of two sections 14 and 15 having their adjacent ends threaded while the opposite ends are formed with hubs 16 and 17 respectively which in turn terminate in trunnions 18 and 19 respectively which are received in the openings 3 and 6. The trunnion 18 has attached to its outer end a disk 20 which is formed with a plurality of graduations 21 adjacent its periphery and it will be understood that when the shaft is rotated the disk will also rotate. A suitable mark 22 is formed on the outer side of the enlargement 2 of the supporting leg 1 and cooperates with the graduations 21 in indicating the proper position at which the head is to be set.

In order to hold the head at various angular degrees, a suitable band 23 surrounds the hub 16 and is provided with suitable extensions which are apertured to receive the bolts 24 which in turn extend through an opening formed in the lug 25 formed on the inner face of the leg 1 as will be clearly seen upon reference to Fig. 5. A suitable thumb nut 26 is threaded on said bolt and is adapted to adjust the pressure of the band on the hub. It will thus be seen that as the thumb nut is tightened the band will be drawn tighter on the hub thus locking the shaft against rotation. The opposite shaft

section provided with a hub 17 is held against rotation by a band 27 which is preferably tensioned so as to only retard the movements of the shaft and this band like that previously described is controlled by means of a thumb nut 28 on a bolt 29 which extends through the lug 30 formed on the inner face of the leg 4.

The tool head is best illustrated in Figs. 6 and 7 and comprises a sleeve or socket 31 provided at one end with a flange 32 having an enlarged bore 33 formed therein. The opposite end of said socket is provided with a reduced cylindrical portion 35 on which the circular plate 36 is secured, which plate is provided with a plurality of graduations 37 and is held in place by the screws 38. A ring 39 surrounds the socket or sleeve 31 between the flange 32 and the ring 36 and is provided with a set screw 40 for engagement against the bottom of a groove 41 formed in the socket. Formed in the flange 32 are radial openings 42 and 43. These openings are arranged at diametrically opposite points and are adapted to receive the screws by means of which the jaw members are retained in place. The jaw comprises a jaw member 44 and a jaw member 45 and the jaw member 44 comprises a semi-circular plate provided with recesses 46 formed in its flat face which recesses are adapted to slidably receive the pins 47 carried by the jaw member 45. The jaw member 45 like the jaw member 44 comprises a semi-circular plate and the adjacent faces of these jaw members are each formed with V-shaped notches 48 which when the jaw members are assembled form a rectangular opening through which the tool projects. A suitable screw 49 is threaded into the jaw member 44 and projects through the opening 42 in the flange 32 while a screw 50 is threaded into the jaw member 45 and projects through the opening 43 in the flange 32. It will be seen that the screw 50 will when turned cause the jaw members to open or close according to the direction of rotation of the screw.

It will be apparent from the foregoing that in use the tool is inserted in the opening formed by the notches 48 between the jaw members 44 and 45 and the screw 50 is then tightened thus causing the jaw members to move into clamping position whereupon the device is swung to the proper position and the set screw 40 is then released so that the tool may be turned after which the screw is tightened and it will be seen that the device may be used in the manner illustrated in Figs. 1, 2 and 3.

While in the foregoing there has been shown and described the preferred embodiment of this invention, it is to be understood that such changes may be made in the combination and arrangement of parts as will

fall within the spirit and scope of the invention as claimed.

What is claimed is:—

1. A device of the class described comprising a pair of legs, a connecting bar connecting the upper ends of said legs to provide a U-shaped frame, a shaft journaled to said legs, a sleeve secured centrally of said shaft, a tool socket rotatably supported in said sleeve, a dial carried by said tool socket and positioned exteriorly of said sleeve to indicate the various positions of the tools carried by the tool socket with relation to said sleeve. 70

2. A device of the class described comprising a pair of supporting legs, a connecting bar connecting the upper ends of said legs to provide a U-shaped frame, lugs extending inwardly from the legs near their upper ends, a shaft rotatably mounted between the legs, bands surrounding the shaft near opposite ends, bolts extending through the lugs and through the bands to tighten the same on the shaft and thereby hold said shaft in various adjusted positions and a tool holder mounted centrally of the shaft for supporting tools to be sharpened. 80

3. A device of the class described comprising a pair of legs, a connecting bar connecting the upper ends of the legs to provide a U-shaped frame, the said legs being apertured slightly below the connecting bar, a shaft journaled in the apertures, a tool holder centrally of the shaft, means to hold the shaft in various adjusted positions and 90 a dial at the end of the shaft to indicate the various degrees of adjustment. 100

4. A device of the class described comprising a pair of legs, a connecting bar connecting the upper end of the legs to provide a U-shaped frame, the said legs being apertured slightly below the connecting bar, a shaft journaled in the apertures, a tool holder centrally of the shaft, means to hold the shaft in various adjusted positions and 105 a dial at the end of the shaft to indicate the various degrees of adjustment, means to adjust the tool holder on the shaft and a dial on the tool holder to indicate the various 110 positions of the tool within the holder. 115

5. A device of the class described comprising a pair of legs, a connecting bar connecting the upper ends of said legs, a shaft journaled between the legs, a tool holder centrally of the shaft, a dial on one end of the shaft to indicate various positions of the tool holder, hubs formed on the shaft near opposite ends, lugs extending inwardly from the legs immediately beneath the hubs, bands surrounding the hubs and bolts extending through the bands and through the lugs to adjust the tension of the bands on the hubs and thereby hold the tool holder in various 120 adjusted positions. 125

6. In a device of the class described, a

tool holder comprising a sleeve, a flange at one end of the sleeve, jaws adapted to fit within the flange, guide pins carried by one of the jaws and extending through the opposite jaw, the flange being provided with a pair of diametrically opposed apertures, a screw carried by one of the jaws, a reduced extension on the end of the screw adapted to fit in one of the apertures, a shoulder formed by the reduced extension to limit the movement of the screw and a screw extending through the opposite aperture to move the cooperating jaw toward or away from the first mentioned jaw in order to clamp a tool in place.

7. In a device of the class described, a tool holder comprising a sleeve, a flange at one end of the sleeve, jaws adapted to fit within the flange, guide pins carried by one of the

5 10 15 20 25 30

jaws and extending through the opposite jaw, the flange being provided with a pair of diametrically opposed apertures, a screw carried by one of the jaws, a reduced extension on the end of the screw adapted to fit in one of the apertures, a shoulder formed by the reduced extension to limit the movement of the screw and a screw extending through the opposite aperture to move the cooperating jaw toward or away from the first mentioned jaw in order to clamp a tool in place, and means to rotatably support the sleeve in various adjusted positions.

In testimony whereof I affix my signature in presence of two witnesses.

LYNN P. McEACHRON.
